UNITED STATES PATENT OFFICE.

EDWARD K. TRIOL, OF SEATTLE, WASHINGTON.

CONCRETE-PAVEMENT CONSTRUCTION.

Application filed February 9, 1922. Serial No. 535,258.

To all whom it may concern:

Be it known that I, EDWARD K. TRIOL, a citizen of the United States, and resident of Seattle, in the county of King and State 5 of Washington, have invented certain new and useful Improvements in Concrete-Pavement Construction, of which the following is a specification, reference being had therein to the accompanying drawing.

10 This invention relates to concrete pavements and to forming the same, the ends sought being: a satisfactory pavement that can be produced rapidly and at low cost by ordinary workmen; that allows expansion; that is readily made of any desired width without losing its advantages; that may rise and fall unequally, to a moderate extent, without cracking; that consists of constituent blocks or areas arranged to 15 transmit load strains from one to another without off-setting at the lines of division; that contains simple and effective metal reinforcement tying its segments or blocks together; that has its consecutive constituent segments so connected that one cannot 20 either rise or fall without the other, and yet may have a plurality of segments removed and replaced together or simultaneously.

25 In the accompanying drawings, which are largely diagrammatic,

Figure 1 is a plan view of a portion of the pavement in place.

Fig. 2 is a perspective view on a larger scale, showing portions of two connected consecutive blocks or segments.

Fig. 3 is a section on the line 3—3, Fig. 2, reinforcement being shown.

Fig. 4 is a similar section through a joint arranged for expansion.

Fig. 5 is a perspective view of a portion of a metal joint-forming member.

Figs. 6, 7 and 8 are plan views of slightly different forms of the member of Fig. 5.

Fig. 9 is an end view of the structure of Fig. 5.

Fig. 10 is a view like Fig. 3 showing the blocks or segments thickened near the joints.

In these figures, 11, 12, 13, 14 represent 50 marginally interlocking concrete slabs, 11 and 12, extending across the way to be paved or surfaced with concrete, and 13, 14 blocks or slabs narrower than the way, to carry, respectively, traffic in opposite directions, both forms being used, when desired, in the same traffic avenue, conditions vary-

ing in different sections. The contiguous margins of successive slabs are interlocked by projections from the lower part of each fitting in corresponding recesses in the margin of the other and barring independent movement of either except longitudinally of the roadway and in the common plane of the slabs. Each slab has, preferably, a shoulder 15 extending downwardly for a short distance from its upper surface, and below this shoulder a series of salient portions 16 alternating with recesses 17, formed by undercutting. The salient portions or projections 16 fit in recesses, like the recesses 17, in the companion slab, and in the recesses 17, fit corresponding projections on the other slab. Preferably all the projections slope downward and are transverse with respect to the general vertical plane of the shoulder 15. Two slabs formed in this manner can be moved perpendicularly to the joint into close engagement, as in Fig. 2, but they cannot move otherwise relatively, to any great extent without 55 breaking the projections 16. When it is desired to increase the strength of these projections without great increase in cost, the slabs are thickened downwardly near the joint, as indicated in Fig. 10.

Slabs such as thus far set forth specifically can be produced in advance of the time of use and stored in any quantity. In many cases, however, it is preferred to form the slabs successively in place on the roadway, and in doing this thin metal, edge-forming members such as shown in Fig. 5 are used. These are or may be formed by providing a plane metal sheet, shearing it from its lower margin upwardly at intervals corresponding to the width of the projections and recesses above mentioned, the cuts extending upwardly to a line as far below the upper edge as the distance between the upper and lower limits of the shoulder 15. At this line, the parts 18, 19 between the cuts are bent alternately in opposite directions at an angle corresponding to the slope of the upper surfaces of the projections 16; and if desired, triangular 105 pieces 20, perpendicular to the plane of the incut margin of the sheet, are secured to the end margins of the laterally bent portions 18, 19. This structure is placed upright upon the base which is to support 110 the slabs, and is usually supported laterally upon one side by stakes 21, 22. Plastic

concrete is then placed upon the opposite side of the form and brought up to its upper edge. If this be allowed to set, the form could be removed and used again, but 5 is preferred to leave it in place and add concrete upon its opposite side to form a second slab.

Preferably this form is perforated as at 23 to allow the passage of reinforcing longitudinal rods 24 passing obliquely through 10 this member from a horizontal plane near the lower side of the slab to a parallel plane near the upper side of the companion slab, as shown in Fig. 3. Other reinforcing rods 15 25 are placed near the planes just mentioned and transverse with respect to the rods first mentioned.

Instead of the form shown in Fig. 5, the forms of Figs. 6, 7 or 8 may be used, the 20 plane sheet having the same upper marginal portion as before, but the lower part being formed by pressing portions 26, 27, Fig. 6, or 28, 29, Fig. 7, or 30, 31, Fig. 8, alternately to opposite sides of the plane upper portion 25 32 of the sheet. These forms require greater initial outlay, but are simpler, and in the end less expensive.

Obviously, the metal form engages the concrete on each face in such manner as to 30 aid in transmitting load strains. It is also clear that the shoulder avoids any thin edge of concrete that might crumble under traffic; and the method of inserting the reinforcing rods seems to need no explanation.

35 To provide for expansion of the pavement two duplicate edge-forming plates such as that of Fig. 5 for example, are used in certain joints where they are parallel and spaced apart, the intervening space being 40 filled with asphalt or other yielding material 40, as shown in Fig. 4.

For allowing change in direction of the edge-forming plate, its upper portion 32 45 may be sheared partly across, as at 33, Fig. 5, and if desired the upper edge of the metal form may lie at a short distance below the upper surfaces of the adjacent slabs, as indicated in Fig. 3.

What I claim is:—

50 1. A broad concrete paving slab having along one side, and at some distance directly below its upper face, alternating projections and recesses with their lateral faces perpen-

dicular to said side and adapted to lie and closely fit in corresponding recesses and projections, respectively, along the margin of a 55 companion slab.

2. A broad concrete paving slab having at its upper side a vertical edge surface and below that surface a horizontal series of 60 spaced projections with downwardly and outwardly inclined upper faces and further having in the lower portion of the slab between consecutive projections a series of recesses adapted to be occupied, respectively, 65 by projections of a similar set on the edge of a companion slab in the same plane.

3. A broad concrete paving slab having at one edge, materially below its upper surface, a series of projections extending beyond the 70 general line of said edge, and further having between said projections a series of recesses extending to the opposite side of said general line.

4. In concrete paving construction, the combination with a metal joint plate having a substantially erect upper marginal portion and below that portion segments bent alternately, in opposite directions to lie in downwardly divergent planes, of concrete slabs, 80 in a plane, fitting opposite sides of said joint plate, respectively. 75

5. A concrete paving slab having above near one margin a shoulder extending downwards to some distance from its upper surface and provided with a series of projections having inclined upper surfaces extending obliquely downward and outward from 85 said shoulder, and further having between 90 said projections recesses adapted to receive like projections on a companion slab, a thin metal plate being placed between the margins and fitting both.

6. The combination with two contiguous 95 concrete slabs each having inclined portions which project into corresponding recesses in the lower part of the companion slab's edge, of a metal plate between said margins and fitting both, and reinforcing rods passing obliquely from the lower portion of one 100 slab, through the interposed plate and held in the upper portion of the other slab.

In testimony whereof I hereunto affix my signature.

EDWARD K. TRIOL.
